UNITED STATES PATENT OFFICE

CHARLES A. JAMISON, OF PHILADELPHIA, PENNSYLVANIA, ASSIGNOR TO PENNSYLVANIA CRUSHER COMPANY, OF NEW YORK, N. Y., A CORPORATION OF NEW YORK

HAMMER MILL

Application filed June 30, 1928. Serial No. 289,502.

My invention relates to hammer mills of the type employing a rotor structure carrying beaters or hammers designed to operate upon material fed into their zone of movement and crush the same by impact.

5 My present invention comprises what may be termed a double acting machine in which the first action of the hammers is to nip portions of material temporarily arrested and held from delivery to the main crushing zone until partially reduced; the material passing to such zone being given further reducing treatment by impact of the hammers before being discharged in the finally crushed state.

10 A further object of my invention is to provide a grate for arresting and/or temporarily supporting the larger pieces or masses of material undergoing treatment while the nipping action takes place; the hammers of the rotor structure passing between the bars of said grate.

15 A further object of my invention is to mount the grate bars in a part of the crusher structure pivotally connected to the main frame so that said bars may be lifted as a whole with such pivotally mounted portion of the crusher structure for repairs or for the purpose of gaining access to the rotor structure carrying the hammers.

20 A further object of my invention is to provide the pivotally mounted portion of the structure with a breaker plate having a series of wear plates, and to provide said bars with supporting means which may serve as a continuation of said wear plates.

25 These and other features of my invention are more fully described hereinafter; reference being had to the accompanying drawings, in which:

30 Figure 1 is a side elevation more or less diagrammatic in character and partly in section, of one form of crushing structure embodying my invention, and

35 Fig. 2 is a plan view of the same, partly in section on the line II—II, Fig. 1.

40 My improved crusher structure may comprise a base 1, having bearings of any usual form, indicated at 2, supporting the shaft 3 of a rotor structure, which rotor structure 45 may comprise spaced disks 4, in which are

mounted rods 5, upon which are hung a series of beaters or hammers indicated at 6. The shaft 3 may be driven by any suitable means common to the operation of similar structures.

The upper portion of the crushing structure may comprise a fixed part indicated at 1^a, including side walls, and a movable part indicated at 1^b; the latter being normally secured in place with reference to the fixed structure by bolts 1^c passing through meeting flanges of the respective parts. In addition the movable portion may be bolted to the base. The movable portion 1^b includes side walls and a breaker plate 7, disposed at one end of the crusher structure, having a punctured ears 8 whereby it may be hung upon a cross rod 9, mounted in the base 1, and upon which such breaker plate may be swung when it is desired to repair or remove the rotor structure or replace the hammers thereof.

55 The inner face of the breaker plate may be provided with wear members 10; one of which is indicated in Fig. 1, and below these wear members I secure a series of grate bars indicated at 11, to said breaker plate. These grate bars are curved as indicated to overlie the rotor structure, and they may be provided with upper and lower projecting portions 11^a at their end adjacent the breaker plate through which bolts 12 are passed; said bolts 60 receiving nuts 12^a for the purpose of securing said grate bars to the breaker plate.

65 The opposite ends of the grate bars may be connected together by a cross bar 13, which may pass through the side walls of the movable portion 1^b of the crusher frame and be held thereto by suitable means; the pins 14, for instance, illustrated in Fig. 2. The fixed portion 1^a of the crusher structure is prefer-

70 ably provided at this point with a cross member 15, which may be bolted, riveted, or otherwise secured to the side walls of the crusher structure, and the surface of this member disposed toward the movable portion 1^b is re-

75 cessed at 16 to form a seat upon which the ends of the grate bars 11 may rest, as clearly indicated in Fig. 1. The apertures in the side walls of the crusher structure through which the ends of the rod or bar 13 pass may 80 be in the form of short slots in order that 79

100

the ends of the grate bars 11 may rest firmly upon the seat formed by the recess 16.

When in the condition of use, the pivotally mounted portion 1^b of the frame carrying the breaker plate and grate bars is bolted or otherwise secured to the fixed portion 1^a supporting the cross member 15; detachable bolts 1^c for such purpose being shown in the drawings, and such movable portion may also be secured to the base.

The curve of the grate bars follows in its greater extent the path of the beaters or hammers so that any material dumped into the crusher and arrested and/or temporarily supported by said grate bars is subjected to a nipping action by the ends of said beaters or hammers, whose path of action is clearly indicated in Fig. 1.

This crusher is designed to act upon what may be termed steam shovel feed which will include portions of rock, ore, coal, and/or the like that will pass freely through the spaces between the grate bars, while other portions too large for such passage will be arrested by the grate bars and temporarily held thereby until the nipping action of the beaters or hammers has so far reduced the larger pieces or masses as to permit their passage between the grate bars to the space below the same where such material will be subjected to further impact by the beaters or hammers 6 to effect the desired reduction.

The faces of the supporting ends 11^a of the grate bars may be disposed in line with the wear members 10 carried by the breaker plate and serve in some measure as a part of the anvil against which the material supported by said grate bars is crushed.

When it is desired to gain access to the rotor structure for the purpose of repair or replacement of the beaters or hammers, or for the purpose of entirely removing the rotor structure, the portion 1^a of the crushing frame carrying the breaker plate 7 may be disconnected from the fixed portion 1^b of the frame by removing the bolts 1^c, and then turned back on its hinge with the cross rod 9, as indicated by the broken lines in Fig. 1. This position of such movable portion also permits removal and replacement of the grate bars 11.

I claim:

1. A crushing structure comprising a hopper for the material to be crushed having its bottom made up of spaced bars in the form of a grate, rotary beaters adapted to pass between the bars of said grate into said hopper, a pivotally mounted support for the bars of said grate to which they are fixed at a point adjacent said pivot, and a transverse support upon which the opposite ends of said grate bars may freely rest.

2. A crushing structure comprising a hopper for the material to be crushed having its bottom made up of spaced bars in the form

of a grate, rotary beaters adapted to pass between the bars of said grate into said hopper, a pivotally mounted breaker plate to which the bars of said grate are connected, a transverse support for the opposite ends of said grate bars, and means connecting the ends of the several bars resting upon said support.

3. A crushing structure comprising a hopper for the material to be crushed having its bottom made up of a plurality of curved grate bars, rotary beaters adapted to pass between the bars of said grate into said hopper, a pivotally mounted support for said grate bars to which they are secured at a point adjacent said pivot, a transverse support upon which the opposite ends of said grate bars may freely rest, and means for connecting the ends of the bars resting upon said support.

4. A crushing structure comprising a hopper for the material to be crushed having its bottom made up of a plurality of curved grate bars, rotary beaters adapted to pass between the bars of said grate into said hopper, a pivotally mounted breaker plate to which said grate bars are connected; one end of each of said grate bars being flanged for such connection, a transverse support for the opposite ends of said grate bars, and means for connecting the ends of the bars resting upon said support.

5. A crushing structure comprising a fixed portion and a pivotally mounted portion providing a hopper for the material to be crushed; said hopper having its bottom made up of spaced bars in the form of a grate, rotary beaters adapted to pass between the bars of said grate into said hopper; the bars of said grate being fixed to said pivotally mounted portion, a transverse support for the opposite ends of said grate bars, and means for connecting the ends of the bars resting upon said support.

6. A crushing structure comprising a fixed portion and a pivotally mounted portion providing a hopper for the material to be crushed; said hopper having its bottom made up of spaced bars in the form of a grate and said pivotally mounted portion including a breaker plate, rotary beaters adapted to pass between the bars of said grate into said hopper; the bars of said grate being fixed to said pivotally mounted breaker plate, a transverse support for the opposite ends of said grate bars, and means for connecting the ends of the bars resting upon said support.

7. A crushing structure comprising a fixed portion and a pivotally mounted portion providing between them a hopper for the material to be crushed; said hopper having its bottom made up of a plurality of curved grate bars, rotary beaters adapted to pass between the bars of said grate into said hopper; said grate bars being fixed to said pivotally mounted portion, a transverse support for the op-

posite ends of said grate bars, and means connecting the ends of the bars resting upon said support.

8. A crushing structure comprising a fixed portion and a pivotally mounted portion providing between them a hopper for the material to be crushed; said hopper having its bottom made up of a plurality of curved grate bars and said pivotally mounted portion including a breaker plate, rotary beaters adapted to pass between the bars of said grate into said hopper; each of said grate bars having a flanged end, means for securing said flanged ends to the breaker plate, a transverse support for the opposite ends of said bars, and means connecting together the ends of the bars resting upon said transverse support.

9. In a crushing structure of the character described, the combination of a frame having a fixed portion, a rotary hammer-carrying member supported by the same, a hopper for the material to be crushed disposed above said rotor structure, bars forming a grate for the bottom of said hopper, a pivotally mounted support to which the ends of said grate bars are connected forming one wall of said hopper, a transverse support carried by the fixed portion of the frame upon which the opposite end of said grate bars may rest and forming the opposite wall of the hopper, and a connection for the ends of said bars resting upon said transverse support.

10. In a crushing structure of the character described, the combination of a frame having a fixed portion, a rotary hammer-carrying member supported by the same, a hopper for the material to be crushed disposed above said rotor structure, bars forming a grate for the bottom of said hopper, a pivotally mounted support to which the ends of said grate bars are connected forming one wall of said hopper, a cross member carried by the fixed portion of the frame upon which the opposite end of said grate bars may rest and forming the opposite wall of the hopper, and a connection carried by the pivotally mounted support for the ends of the bars resting upon said cross member.

11. In a crushing structure of the character described, the combination of a frame including a base, a fixed portion secured to said base and a portion pivotally connected to said base, a rotary hammer-carrying member supported by the base, a hopper for the material to be crushed provided by said fixed and pivotally mounted portions and disposed above said rotor structure, bars forming a grate for the bottom of said hopper; said bars having one end fixed to said pivotally mounted portion, a shelf carried by the fixed portion of the structure upon which the opposite end of said grate bars may rest, a connection for the ends of said bars resting upon said shelf, and means for

securing the pivotally mounted portion of said frame to the fixed portion thereof.

12. In a crushing structure of the character described, the combination of a frame including a base, a fixed portion secured to one end of said base and a portion pivotally connected to the opposite end of said base, a rotary hammer-carrying member supported by the base, a hopper for the material to be crushed provided by said fixed and pivotally mounted portions and disposed above said rotor structure, bars forming a grate for the bottom of said hopper; said bars having one end fixed to said pivotally mounted portion, a cross member forming a shelf carried by the fixed portion of the structure upon which the opposite end of said grate bars may rest, a rod passing through the walls of the pivotally mounted portion and providing a connection for the ends of said bars resting upon said shelf, and means for securing the pivotally mounted portion of said frame to the fixed portion thereof.

13. A crushing structure comprising a base, a fixed frame portion surmounting said base, a pivotally mounted frame portion also surmounting said base; said frame portions being normally secured together and providing a hopper for the material to be crushed, a rotary hammer-carrying element supported in said crushing structure, a cage or screen disposed below and cooperating with the hammers of said hammer-carrying element, a series of grate bars disposed above said cage or screen and forming the bottom of said hopper; said hammers passing between said bars and into said hopper, and a breaker plate carried by said pivotally mounted portion to which one end of each of said grate bars is secured; said grate bars serving to arrest large masses of the material to be crushed which may be subjected to nipping action by the hammers for reduction prior to passage to the space below the grate for further action by the hammers of the hammer-carrying element.

14. A crushing structure comprising a base, a fixed frame portion surmounting said base, a pivotally mounted frame portion also surmounting said base; said frame portions being normally secured together and providing a hopper for the material to be crushed, a rotary hammer-carrying element supported in said crushing structure, a pivotally mounted cage or screen disposed below and cooperating with the hammers of said hammer-carrying element, a series of curved grate bars disposed above said cage or screen and forming the bottom of said hopper; said hammers passing between said bars and into said hopper, and a breaker plate carried by said pivotally mounted portion to which one end of each of said grate bars is secured; said grate bars serving to arrest large masses of the material to be crushed.

which may be subjected to nipping action by the hammers for reduction prior to passage to the space below the grate for further action by the hammers of the hammer-carrying element until finally crushed to the desired size for passage through said cage or screen.

In witness whereof I have signed this specification.

CHARLES A. JAMISON.
